UNITED STATES PATENT OFFICE.

WILLIAM HUTTON, OF PHILADELPHIA, PENNSYLVANIA.

IMPROVEMENT IN FLASKS FOR CASTING PULLEYS.

Specification forming part of Letters Patent No. 159,097, dated January 26, 1875; application filed August 11, 1874.

To all whom it may concern:

Be it known that I, WILLIAM HUTTON, of Philadelphia, Pennsylvania, have invented an Improved Flask for Making Pulleys and other Circular Forms; and I do hereby declare the following to be full and correct description of the same, reference being had to the accompanying drawings, in which—

Figure 1 represents my flask, partly in section, with the pattern of the hub and arms in place. Fig. 2 is a sectional view of my flask, showing the mold with the pattern withdrawn, ready for casting. Fig. 3 represents the inside flask with the sweep in the act of sweeping up the outside face of the pulley, and Fig. 4 is the sweep in position to sweep up the inside face of the pulley.

The object of my invention is to form a mold for casting pulleys or other circular forms without the use of patterns; and it consists in forming the flask in two parts, one for the inside face of the pulley or other circular form, together with the hub, arms, &c., and the other for the outside face, by sweeping up the two faces by means of sweeps.

In the drawings, A represents the bottom part of the outside flask, and A' the top part or "cope;" B, the bottom, and B' the cope of the inside flask. In the inside flask the hub and arms of a pulley-pattern, M, are molded up in the usual manner, except that the arms extend through orifices in the side of the flask, and extend outward, as shown at m. After the inside of the inner flask is properly rammed and the cope in place, the outside of the flask B B' is rammed up between flanges b and b' with sand, there being points or projections i upon the surface, for keeping the sand in place. This surface of sand is then swept by the sweep C, as shown in Fig. 4, the flanges b and b' being used as guides for the sweep; the sweep, in its revolutions, just passing the ends of the pattern of the arms m, until a true surface of the rim of the pulley is formed. The outer flask is then secured together by means of the lugs, in the usual manner, and the inside, between the flanges a and a', is rammed up with sand, the projections i holding the sand, and swept down with the sweep

D, as shown in Fig. 3, until an even surface is formed for the outside surface of the rim of the pulley. The flasks are now put one within another, and they are ready for casting. Of course other circular forms may be cast in the same manner; but I illustrate my invention with a pulley-mold; also, other flasks may be used, such as "snap-flasks," which may be an advantage in sweeping up.

When a large rim is to be cast, rings may be placed between the cope and bottom of both inner and outer flasks, and the same desired result accomplished.

The operation of my device is as follows: Take one half of the pattern of the hub and arms of the pulley, and lay it upon a following-board, and half of inside flask over it, the half-pattern coming in the center of the orifices in the sides of the flask. Fill the space around the pattern with sand, and ram up. Repeat the same process with cope of inside flask, and put the two together. Ram up the outside with sand, and sweep up with the straight sweep C. Cut the joint with a cutting-tool, lift the cope off, remove the patterns, and dress up. Fill up the outside of the flask a' with sand, and ram. Sweep with the convex sweep D, put the two flasks together, make a gate in the top, and it is ready for casting.

Having thus fully described my invention, what I claim, and desire to secure by Letters Patent, is—

In a flask for making pulleys, the combination of an outer flask, consisting of the bottom A and cope A', provided with the flanges a a', and an inner flask, consisting of the bottom B and cope B', provided with the flanges b and b', and adapted to have the molds formed therein by means of the sweeps C and D, substantially as described.

The above specification of my said invention signed and witnessed, at Philadelphia, this 8th day of August, A. D. 1874.

WILLIAM HUTTON.
